AMMUNITION AND FIREARM

Helge Rost, Mexico, D. F., Mexico

Application May 25, 1935, Serial No. 23,412

21 Claims. (CL 89—7)

The present invention relates to new and useful improvements in firearms of the so-called powderless type and has reference as well to a particular ammunition used in connection therewith.

An object of this invention is to provide a new explosive charge for firearms of the character hereinafter described, which will have considerably higher explosive powers than ordinary gun powder and the like, and which can be manufactured more cheaply than other types of explosives used for the same purpose.

Another object of this invention is to provide an explosive charge of this character, which will be unaffected by shock, friction and temperature, and which will not deteriorate when stored for an indefinite period.

Another object of this invention is the provision of an explosive charge which will be free from all danger of self-ignition.

Another object of the invention is to provide a new type of cartridge which will contain an explosive charge of the character hereinafter described and which will consequently have all of the advantages inherent in the particular charge used therein.

Still another object of this invention is to provide a construction for a firearm which is particularly adapted for use in connection with my new type of cartridge.

I accomplish these objects by means of the present invention which comprises briefly, an explosive charge consisting of two chemical substances which are segregated up to the moment the gun is fired, at which time they are combined to effect an explosion. The explosive charge according to the present invention consists, on the one hand, of a hydrocarbon or its derivatives such as gasoline, and on the other hand, of an oxygen-liberating compound, as for instance chlorate of potassium. By varying the proportions of these two ingredients constituting the explosive charge, varying degrees of the speed of combustion may be obtained.

According to the present invention the gasoline is injected into a compartment of the gun barrel forming a combustion chamber and the oxygen-liberating compound is either placed in the combustion chamber or disposed inside a cartridge. In the latter case, provision is made for ready admission of the gasoline to the oxygen-liberating compound which may be accomplished by perforating the cartridge. Upon compression of the air and atomization of the fuel, the fuel-air mixture will penetrate into and min-

gle with the oxygen-liberating compound. In this construction ignition may be produced by electric sparks or by a sufficient compression of the air and the gaseous fuel, while the temperature is raised to a point where spontaneous combustion will occur.

Instead of disposing the oxygen-liberating compound within the cartridge and injecting the gasoline from the outside, both the oxygen-liberating compound and the gasoline may be disposed in separate compartments inside the cartridge. Ignition may be produced by any known means. Thus, in the case where both explosive substances are disposed within the cartridge, ignition can be produced by means of the usual firing pin striking a fuse cap provided on the bottom of the shell.

According to this invention the combustion of the explosive charge is greatly accelerated due to the oxygen-liberating compound which, under pressure, will decompose rapidly at raised temperatures, liberating the vital oxygen. The latter together with the oxygen contained in the compressed air accelerates the combustion of the hydrocarbons.

Another advantage of the present invention resides in the fact that complete combustion takes place inside the gun barrel when a shot is fired. It is a well known fact that ordinarily a burst of flames issues forth from the mouth of the gun barrel when a shot is fired because the unburnt gases, when expelled from the gun absorb oxygen from the surrounding atmosphere. However, when using cartridges in accordance with the present invention, the burst of flames and the attendant flash of light will be lacking completely because complete combustion will take place inside the gun barrel. The flashes of light ordinarily produced when a shot is fired can be seen from a great distance, particularly at night. This constitutes a grave strategic disadvantage in that the flashes of light betray the position of the gun. All such danger is overcome by the present invention.

The present invention may be practiced either in connection with the type of guns now in use or with the special gun construction described in the following. Best results will be obtained by means of this new gun which will not only greatly increase the range of fire and give greater penetrating force to the projectiles, but also substantially reduce the cost of operation of the gun.

The following table listing the energies available in the various types of explosives will convey

some idea of the great superiority of the ammunition of the present invention.

	B. t. u. per pound
Black powder	1,230
5 Pure nitrocellulose	2,000
Solar oils	18,000
Kerosene	19,000
Gasoline	20,000
Acetylene	21,500

- 10 The great advantages of this invention will be still more apparent when considering the fact that chlorates for explosive purposes are much cheaper than other explosives (the cost of chlorate being about half of that of dynamite) 15 and that pure chlorate can be manufactured and transported with incomparably greater safety than ordinary explosives generally employed in the armament industries today. Hydrocarbons, on the other hand, are available everywhere at 20 low cost.

The present invention is applicable to all types of ammunition and firearms. It may be used in connection with simple, hand-operated single-shot guns with the same advantages as in the 25 case of automatic rapid firing guns and ordnances of every caliber.

The recoil energy developed when the gun is fired may be utilized for feeding ammunition and fuel, or for compressing air, cooling the explosion 30 chamber and for similar purposes. Various spring arrangements, as well as hydraulic and pneumatic arrangements may also be combined with the present invention.

Several embodiments of my invention are illustrated in the accompanying drawings in which—

Figure 1 is a vertical sectional view through the breech of a gun which is provided with a combustion chamber and a spark plug;

Figure 2 is a vertical sectional view through the breech of a similar gun construction modified to include a firing pin;

Figure 3 is a bottom plan view of the type of ammunition shown in Figure 1;

Figure 4 is a bottom plan view of the type of ammunition shown in Figure 2;

Figure 5 is a view partly in elevation and partly in section of one form of cartridge according to the present invention;

Figures 6, 7 and 8 are sectional views of modified forms of the cartridge according to the invention;

Figure 9 is a diagrammatic view of a gun and cartridge with cooling system in accordance with this invention.

55

The gun

In the drawings, 1 denotes a gun barrel attached to the casing 34 which is provided with a loading chamber 5. The latter has a loading aperture 2 and a conical extension adjacent the rear end of the barrel 1. A hollow cylinder 3 is provided with a conical head 6 and is movably disposed in the loading chamber 5, head 6 fitting tightly into the conical extension thereof. This 65 hollow cylinder 3 which constitutes the breech of the gun is provided with packing rings 4 to prevent escape of air and gas from the loading chamber 5 into the cylinder 3 or vice versa. A spark plug 10 and a fuel injector 11 open into 70 the conical extension of the loading chamber. Conical head 6 is provided with openings 7 and 8 allowing the discharge of sparks and fuel, respectively, to the interior of the conical head 6 forming a combustion chamber 9. The latter is 75 closed up against the barrel 1 by a projectile 12

and against the interior of the cylinder 3 by a movable piston 19. Piston rod 21 serves for actuating the piston 19 inside the cylinder 3. Piston rings 20 are provided on the piston 19 to prevent air or gas from passing from the combustion chamber 9 to the interior of the cylinder 3. Washers 22, 26 and 27 are solidly attached to the rod 21 and serve for guiding the same inside the cylinder 3. The latter is provided with a slot 25 permitting back and forth movement of the handle 23 which is integrally attached to a washer 22 and serves for actuating the piston 19 within the casing 3. Washer 22 also comprises a downward projection 24 provided with an aperture 25 which is adapted to engage a lock spring 30 attached to the cylinder 3. When the handle 23 is moved to the right so that washer 22 and extension 24 take the position 31 indicated in dotted lines, lock spring 30 will lock the extension 24, and with it the piston 19 to the cylinder 20 3, so that continued movement of the handle 23 to the right will result in a joint movement of the piston 19 and the movable cylinder 3 interlocked therewith. 33 designates the furthest righthand position to which the cylinder 3 and the piston 19 25 may be moved. In this position the loading aperture 2 of the loading chamber 5 will be fully exposed. Cylinder 3 is provided with an internal cylinder head 28 with which is associated pressure spring 29 exerting a forward pressure on the washer 22. Washer 27 is attached to the end of the rod 21 and forms a stop to the leftward movement of the piston 19. Spring 32 exerts a forward pressure on the cylinder head 28 urging the cylinder 3 to the left. Springs 29 and 32 in 35 conjunction with the preliminary independent backward movement of the piston 19 will assure sufficient absorption of the recoil shock to produce smooth operation of the gun. The loading aperture 2 may be kept open by means of a lock 40 device (not shown) retaining the cylinder 3 in its extreme righthand position. No such locking device will be needed in the case where the ammunition is fed automatically. The downward projection 24 may be employed for actuating a fuel supply pump. In Figure 1, 35 designates the plunger of the pump, 36 constitutes the piston and 37 and 38 represent the admission and delivery valves, respectively, of the pump. Fuel is fed through a connection piece 40'. 40 50 represents a filter disposed near the connection piece 40'. The parts of the gun surrounding the combustion chamber 9 are provided with cooling fins 41 consisting of a material of high thermal conductivity, e. g. aluminum.

In the embodiment shown in Figure 1, a projectile 12 is inserted in the gun barrel 1. Projectile 12 is supported by a shell 14 containing a porous oxygen-liberating cartridge or stick 15. The copper strip 13 attached to the projectile 12 60 serves the double purpose of providing a tight seal against the escape of gases from the combustion chamber 9, on the one hand, and for imparting a rotary movement to the projectile 12 on its travel through the rifled gun barrel 1, on 65 the other hand. The shell 14 is provided with a closure disc 17 having perforations 18 for the purpose of admitting fuel to the oxygen-liberating stick contained therein. Channel 16 extending through the stick 15 assures ready distribution 70 of the injected fuel.

The mode of operation of the gun illustrated in Figure 1 is as follows:

The loading chamber 5 is exposed by moving handle 23 to the right. In the position 31, shown 75

in dotted lines, the lock spring 30 entering the aperture 25 of projection 24 will lock the piston rod 21 to the cylinder 3 which will be carried along when the movement of the handle 23 is continued. Ammunition is then loaded through the loading aperture 2, the handle 23, piston 19 and cylinder 3 are moved to the left to place the projectile 12 in firing position, as shown in Figure 1. Simultaneously therewith, the air in the combustion chamber 9 is compressed due to the forward stroke of the piston 19. At the same time, projection 24 actuates the plunger 35 of the fuel pump causing injection of fuel into the combustion chamber 9. The atomized fuel and compressed air mixture penetrates into oxygen-liberating cartridge 15 and the combustion mixture is ignited by means of spark plug 10.

The gun construction illustrated in Figure 2 closely resembles that of Figure 1. The main difference between the two constructions resides in the fact that the construction shown in Figure 2 is adapted for use with a different type of cartridge. Instead of a spark plug, the gun is provided with a firing pin 48. The following is a detailed description of Figure 2.

In this construction, 42 designates the compression chamber which is provided with an aperture 45 for the injection of fuel from the fuel injector 11. The gun breech is formed by a movable cylinder 44 which is provided with piston rings 46 serving as gas checks. Piston 47 moving within the cylinder 44 comprises a firing pin 48 which is movably disposed in a cavity 49 provided in the piston 47. Piston rings 50 are attached to the piston 47 to make a tight seal between the latter and the inner wall of the cylinder 44. The cartridge 12 adapted for use in this gun comprises a fuse cap 51 provided with a perforated disc 17 disposed on the shell 14. The latter comprises an enlarged chamber 53 in which the oxygen-liberating stick 15 is disposed. Chamber 53 is of such dimensions that it constitutes a continuation to compression chamber 42 of the gun. Perforated disc 17 forming the bottom wall of the shell 14 is kept in position by studs 52 of the shell. Instead of the cooling fins 41 of the construction shown in Figure 1, Figure 2 comprises a cooling jacket 54 having an expansion chamber 55 and an inlet opening 56 for the cooling medium.

The operation of the gun shown in Figure 2 is the same as that of Figure 1, except that in this gun the projectile is fired by firing pin 48 striking the fuse cap 51.

The cooling arrangement forms an important part of the present invention because of the high thermal energies developed during combustion of the hydrocarbons in the presence of oxygen. In rapid fire machine guns the use of an efficient cooling system becomes all important.

The preferred type of cooling system according to the present invention, which is simple and practical in construction and of high efficiency as well, is a system in which compressed air is used as a cooling medium. Such an arrangement is shown diagrammatically in Figure 9 in which 100 designates the gun barrel, 101 a projectile, 102 the combustion chamber and 103 the breech lock piston. The latter is attached to a rod 104 which also carries a compressor piston 105 cooperating with compression chamber 106. Air is supplied to the compression chamber 106 by an intake valve 107 and fed to a compressed air tank 109 through valve 108. Expansion valve 75 110 is interposed between tank 109 and the ex-

pansion and cooling chamber 111 surrounding the combustion chamber 102. The spent air is returned to the outer atmosphere through an outlet 112.

The cooling system operates as follows: When a shot is fired, the breech lock piston 103 moves to the right, causing compressor piston 105 to compress the air stored in the compression chamber 106. The air thus compressed is delivered to compressed air tank 109 whence it is conveyed to the expansion chamber 111 through valve 110. The latter should be adjusted in such a way that the amount of air allowed to pass through per time unit will correspond to the amount of air compressed per time unit. The air having passed 15 the expansion valve 110 is allowed to expand suddenly in the expansion chamber 111 whereby the temperature of the air is considerably reduced. The expansion chamber surrounds those parts of the gun that are subjected to the greatest amount of heat, namely, the combustion chamber 102 and the rear end of the barrel 100. The latter are effectively cooled by the steady streams of cool air circulating in the expansion chamber 111. After passing through the expansion 25 chamber 111, the air is returned to the outer atmosphere through outlet 112.

It will be obvious that instead of atmospheric air as a cooling medium, a closed system using any kind of gas or liquid adapted for refrigeration may be used. In such a modification, the recoil action of the breech may be utilized in a similar manner.

In the embodiment illustrated in Figure 9 the recoil action of the movable breech is used for 35 operating the cooling mechanism. An object of this invention is to use the recoil action of the gun generally and I do not wish to be understood as limiting my invention to the exact construction shown in Fig. 9. Thus, besides the breech, any 40 part of the gun performing a recoil movement when a shot is fired may be utilized for actuating the cooling mechanism.

Figure 3 is a bottom plan view of the type of cartridge shown in Figure 1. 58 designates the 45 closure disc which preferably consists of fibrous material. Disc 58 is embraced by the shell wall 57 and provided with apertures 59 for establishing communication between the combustion chamber and the interior of the shell.

Figure 4 represents a closure disc for use in guns of the type illustrated in Figure 2. This closure disc differs from the closure disc shown in Figure 3 in that this disc comprises a fuse cap 60.

In accordance with the present invention the combustion of the explosive charge may be so adjusted that a uniform pressure equaling the mechanical resistance for which the gun was constructed is maintained in the gun until the projectile has left the muzzle. This result may be obtained by so proportioning the oxygen-liberating compound with respect to the hydrocarbon compound that combustion takes place step-wise and a fairly constant pressure will prevail in the 65 barrel even after the projectile is started on its way. This feature may be further extended, in accordance with the present invention, by continuing injection of fuel into the combustion chamber after commencement of combustion. 70 Of course, this continued fuel injection will only be possible where the injectors and fuel admission valves are of sufficiently strong construction to withstand the high pressures developed during explosion.

Another method of obtaining the same result consists in exploding successively secondary or additional charges provided in the rear of the projectile. A projectile will serve this purpose best if its rear portion is constructed as a hollow shell open at its end and filled with explosives which will ignite shortly after the projectile is started on its way. Ignition for these secondary charges may be produced either by the high pressure of the original charge or by means of a timing device. If secondary charges are used ignition may either take place while the projectile is still in the barrel or it may be deferred until after the projectile has left the barrel. In the latter case the projectile will behave as a skyrocket, propulsion resulting from the counter-pressure of the escaping gases. In such projectiles the secondary charges should be separated securely from the main firing charge.

An outstanding advantage produced by the guns of the present invention is the uniform velocity imparted to the projectile. By increasing the size of the combustion chamber throughout the barrel, by deferred combustion and successive explosions, a constant pressure of expanding gases may be obtained throughout the barrel which will be lower than the pressure present in ordinary guns in which a single explosion occurs. Owing to this constant pressure the guns of the present invention give the projectile an ideal, uniform velocity. In addition, heavier projectiles may be used, yet the range of the gun and the penetrating power of the projectiles will be increased.

Another advantage of this invention is the use of a movable plunger and cylinder whereby the gun is made to operate on the same principle as a four-cycle explosion motor. The fact that there is no practical limit to the length of the plunger stroke also deserves consideration, particularly if guns are operated at varying altitudes, having a different density of air. In such cases higher compression of the air will be a decided advantage.

The firearms described hereinbefore and illustrated in the drawings represent simple hand-operated guns. It is obvious that the features of those constructions may be readily transferred to all kinds of guns such as automatic machine guns, cannons and ordnances of any and every caliber.

Ammunition

The following is a description of the new type of ammunition according to the present invention, which is adapted particularly for use in connection with the firearms hereinbefore described.

The cartridge shown in Figure 5 comprises a shell 62 containing a porous oxygen-liberating stick 66 consisting, for instance, of chlorate or perchlorate of potassium, sodium or ammonium. Closure disc 64 provided with apertures 65 rests on studs 63 of the shell 62. 67 is a solid disc separating the interior of the shell 62 from the interior of the projectile 61. 66' designates a channel penetrating through the oxygen-liberating stick 66 and providing ready access thereto. Metal rings 61' disposed on the projectile 61 serve as gas checks and for imparting rotation to the projectile. Projectile 61 comprises a fuse cap 68 and a plurality of explosive charges 69 separated from one another by discs 70. Discs 64, 67 and 70 preferably consist of fibrous material.

The projectile is fired by causing the oxygen-

liberating stick 66 to absorb a combustible containing a hydrocarbon or a derivative such as gasoline, kerosene, gas oil, crude oil, mononitrotoluol, mononitrobenzol, or a solid, liquid or gaseous combustible of suitable composition. If gasoline is used it will be admitted under proper pressure to oxygen-liberating stick 66 through perforations 65 and the channel 66'. The combustible mixture thus obtained may be ignited by means of sparks or by raising the temperature sufficiently to produce spontaneous combustion. Combustion within the shell 62 will eject the projectile 61 and set off the fuse cap 68 causing successive explosion of the charges 69 contained in the projectile.

The cartridge shown in Figure 6 comprises a shell 72 containing an oxygen-liberating stick 75 and a vessel 74 consisting for instance of gelatine and containing a hydrocarbon derivative such as liquid gasoline or kerosene or a combustible oil, or a carbon powder or a gaseous fuel-like acetylene. 76 designates the combustion chamber inside the shell 72. The latter is closed at its bottom by a solid closure disc 73' provided with a fuse cap 73. For firing this projectile no explosive need be admitted from the outside. The projectile is fired by striking the fuse cap 73 causing a vessel 74 to break, whereby the gasoline or other hydrocarbon contained therein is released and mixes with the oxygen-liberating compound. The resulting mixture when ignited produces combustion.

Figure 7 shows a projectile 77 provided with a cavity 78 containing a hydrocarbon. The oxygen-liberating stick 82 is disposed in the combustion chamber 83 of shell 80. 79 designates a seal closing cavity 78, and 81 is the fuse cap provided on the solid closure disc 81' at the bottom of the shell 80. The projectile is fired by striking the fuse cap 81 causing rupture of the seal 79. Combustion will result when the hydrocarbon contained in the cavity 78 penetrates into and mixes with the oxygen-liberating stick 82, ignition being produced by the flame of the exploding fuse cap.

Figure 8 shows a projectile 84 carried by a shell 88 containing the oxygen-liberating stick 91. 92 designates the combustion chamber of the shell 88, 89 represents a fuse cap and 90 is a channel extending through the oxygen-liberating stick 91. The projectile 84 is provided with a hydrocarbon containing a cavity 86 which is separated from the remaining parts of the projectile by a solid wall 85 and from the interior of the shell 88 by a seal 87. 94 designates a second oxygen-liberating stick which is placed adjacent to a hydrocarbon vessel 93 disposed in a combustion chamber 95. Shrapnel balls 96 are disposed in the forepart of the projectile 84 which is penetrated by a time fuse channel 97 leading to a fuse cap 99. A timing device of known construction is disposed at 98.

By striking the fuse cap 89 the seal 87 is broken and the content of the cavity 86 mixes with the oxygen-liberating stick 91 which mixture, when ignited, causes combustion which will result in the ejection of the projectile 84. Then, the time fuse 97 actuates fuse cap 99 causing the hydrocarbons contained in the vessel 93 to react with the oxygen-liberating stick 94. The resulting explosion will burst the walls of the projectile 84, discharging the shrapnel balls 96 contained therein.

In the type of cartridge illustrated in Figures 6, 7 and 8, gaseous fuel may also be used, e. g.,

acetylene and acetone under pressure may be employed to advantage. The acetone, acting as a solvent of acetylene minimizes the danger of explosion. Gaseous fuels may either be filled up in separate vessels and disposed at the rear of the projectile or the projectile proper may be provided with a rear chamber in which compressed gases may be stored. The gases are liberated when the gun is fired. This may be done for instance by striking a fuse cap. The liberated gases will react with the oxygen-liberating compound when the charge is ignited. Continuous combustion may be achieved by storing in the projectile a sufficient quantity of compressed gaseous fuel and allowing the same to escape gradually. Such continuous combustion will produce a constant pressure in the gun barrel which will be maintained until the projectile has left the barrel.

20 The arrangements herein described may equally well be used for shell bursting charges, shrapnel and the like as shown in Figure 8. In such case, care must be taken that a solid separation wall such as 85 separates the bursting charge from the propelling charge. If no propelling charge is provided, the rear part of the projectile may be utilized of course for bursting purposes. Explosion for the bursting charge may be produced by any known means such as a time fuse, 25 percussion cap or the like.

30 The present invention affords many great advantages. Pure chlorate of potassium for instance, which is preferably used as oxygen-liberating substance, is practically insensitive to friction and shock. Experiments have demonstrated this fact: for instance, a 20 lb. weight was dropped upon pure chlorate of potassium from a height of more than thirty feet without producing explosion. Moreover, chlorate is not 35 hydroscopic, nor is it sensitive to cold. It may be stored indefinitely and will not decompose, differing herein particularly from ammonium or nitrogen-containing explosives. Chlorate is cheaper than any other explosive of the same 40 potential energy and may now be manufactured 45 on a large scale by electrolytic processes utilizing solutions of chloride of potassium or sodium. The large quantities of electric energy used up in those processes may properly be said to be stored in the chlorate produced, ready to be given up instantaneously when the chlorate is 50 combined with a hydrocarbon under pressure at raised temperature. The combination of these two chemicals create tremendous energies which 55 compare most favorably with the energy produced by the common explosives now in use. Finally, it should be observed that the use of the combined explosive according to the present invention removes almost completely all danger 60 of premature explosion in the gun because the two components of the explosive charge are really not explosive until they combine under pressure. But according to the present invention injection and compression of the mixture can 65 take place only after the loading chamber of the gun has been closed.

I claim:

70 1. The combination with a firearm comprising a closed chamber and a combustible in said chamber, of a cartridge disposed inside the firearm and comprising an oxygen liberating compound, and means for combining the latter with the combustible inside the firearm to produce explosion.

75 2. A firearm comprising a receiving means, an

oxygen liberating compound disposed therein, an injector associated with the firearm, and a combustible adapted to be injected by said injector into said receiving means and to react with the oxygen liberating compound contained therein 5 and means to ignite the mixed combustible and oxygen liberating compound, to produce explosion.

3. The combination with a firearm comprising a combustion chamber, an injector and a combustible adapted to be injected thereby into the combustion chamber, of a projectile disposed adjacent to said combustion chamber and comprising an oxygen liberating compound adapted to react with the combustible to produce explosion. 10 15

4. The combination claimed in claim 3, comprising means for producing ignition in the combustion chamber.

5. The combination claimed in claim 3, in 20 which said firearm comprises a firing device and the said projectile is provided with a firing means adapted to be operated by said firing device.

6. The combination with a firearm comprising a closed chamber and a combustible disposed in 25 said chamber and consisting of a substance belonging to the class of hydrocarbons, of a cartridge disposed in proximity to said chamber and comprising an oxygen liberating compound adapted to combine with the said combustible in- 30 side the firearm to produce explosion.

7. The combination with a firearm comprising a combustible consisting of liquid gasoline, of a cartridge carrying a charge consisting of dry 35 chlorate of potassium disposed close to said gasoline and adapted to combine with the same inside the firearm to produce explosion.

8. The combination of a firearm with a composite explosive charge therefor, consisting of a liquid combustible and an oxygen liberating com- 40 pound separated from each other, and means for combining and igniting the said combustible and the oxygen liberating compound inside the firearm to produce explosion, said liquid combustible being a substance belonging to the class of hydro- 45 carbons.

9. A firearm comprising a casing provided with a loading chamber, a barrel supported by the casing, a breech consisting of a hollow cylinder movably disposed in said loading chamber, a piston disposed in said cylinder and movably mounted with respect to the barrel, the forward part of said cylinder forming a combustion chamber. 50

10. A firearm comprising a casing provided with a loading chamber, a barrel supported by 55 said casing, a breech consisting of a hollow cylinder movably disposed in said loading chamber, a plunger disposed in said cylinder and movably mounted with respect to the barrel, the forward part of said cylinder forming a combustion 60 chamber, and a fuel injector adapted to inject fuel to the interior of said combustion chamber.

11. A firearm as claimed in claim 10, in which said cylinder is provided with a locking member and said plunger is provided with means 65 engageable with said locking member for interlocking the said cylinder and plunger.

12. A firearm as claimed in claim 10, in which said fuel injector includes a fuel pump and said movable plunger comprises means for actuating 70 said pump when the plunger is moved.

13. In a firearm as claimed in claim 10, a spark plug for igniting the charge contained in the said combustion chamber, piston rings on the said cylinder and plunger to prevent escape of air and 75

- gases, a locking member disposed on said cylinder, means attached to said plunger and engageable by said locking member, and actuating means for moving the said plunger.
- 5 14. A firearm as claimed in claim 10, comprising cooling means disposed adjacent to the said combustion chamber of the firearm.
15. A firearm comprising a casing provided with a loading chamber, a barrel supported by 10 said casing, a breech consisting of a hollow cylinder movably disposed in said loading chamber, a plunger movable in said cylinder, a firing pin associated with said plunger, and a fuel injector for injecting fuel to the inside of said movable 15 cylinder forming a combustion chamber.
16. A firearm as claimed in claim 15, comprising locking means for interlocking the plunger and the cylinder and a jacket for a cooling medium adjacent to the combustion chamber of the 20 firearm.
17. A firearm as claimed in claim 15, comprising a cylinder closed at one end to form a compression chamber for the plunger, intake and outlet valves for a cooling medium provided on said 25 compression chamber, and a cooling jacket disposed adjacent to the combustion chamber of the firearm and connected with said compression chamber to receive the compressed cooling medium therefrom.
- 30 18. A cartridge for firearms and the like, comprising a shell and a projectile adapted to be ejected therefrom, said shell containing a solid oxygen liberating compound, the major part of the rear of said shell being open, whereby the same is adapted to rapidly admit a combustible to said compound, the latter being provided with relatively large pores, whereby the said compound is capable of rapid mixture with a combustible admitted thereto.
19. The method of ejecting a bullet from a firearm, comprising a combustion chamber and an oxygen liberating compound disposed therein, 10 which method consists in injecting into the combustion chamber a hydrocarbon adapted to combine with said oxygen liberating compound, igniting the mixture to produce combustion and to propel the bullet, and continuing thereafter 15 to inject the hydrocarbon into the combustion chamber, in order to maintain a uniform pressure behind the bullet until its ejection from the firearm.
20. The combination with a firearm comprising 20 a receiving means and one component of an explosive charge disposed therein, of a cartridge disposed in said firearm and comprising the second component of said explosive charge, said second component being of solid constitution, and 25 means for combining the said two components inside the firearm to produce an explosive mixture.
21. The combination claimed in claim 6, in which said combustible consists of gasoline. 30

HELGE ROST.
